SHOE CONSTRUCTION FOR PREVENTING
DEFORMATION OF THE FOOT

Simon Joseph Wikler, Baltimore, Md.

Application March 10, 1950, Serial No. 148,851

2 Claims. (Cl. 36—8.5)

1

This invention relates to an improvement in shoes and more particularly to a shoe which prevents deformation of the foot.

In the past many different designs and construction of shoes have been proposed; however, generally the shoes now in use are narrowed and convex in the region of the tuberosity of the fifth metatarsal bone, in a manner which causes this structure to be compressed and frequently causes elements of the structure to ride on the upper of the shoe rather than on the sole. The elements mentioned are important weight bearing components and the insufficiency of room in a shoe for them are serious handicaps to the efficient functioning of the human foot and interferes with the normal flow of weight and force to the toes.

Further, the toe room in the shoes now generally in use is narrower than the normal width of the toes, and in many instances the toe room in the shoes is smaller than the width of the already deformed and compressed toes. With insufficient width provided in the toe area of the shoe, the toes are cramped and deformed and are unable to discharge their normal functions. In addition due to the resulting pressure and friction of the compressing shoe, there develop corns, bunions, hammer toes, ingrown nails, and the like. In addition in present shoes inadequate space is provided for the spreading of the middle toes and abduction of the great and small toes. The prolonged non-use of such movements causes these powers to be largely lost. It has been found extremely important to the health of the individual to be able to spread the toes and particularly to be able to abduct the great and little toes of each foot. Not only are these movements essential when the foot is bare but also when the shoe is worn. When shoes that do not permit these functions of the toes are worn over a long period, the human body is forced to make certain gravitational adjustments in posture in order to remain upright. Due to the inability to bear weight fully on the outer side of the foot and the insufficient room for expansion of the toes, the inner side or arch of the foot is used resulting in the disease known as fallen arches. It is essential to the health of the individual to expand the forefoot in order to meet superimposed gravitational demands and still retain proper balance and support. This lack of facility to spread the toes and properly bear the weight affects almost every part of the human anatomy since the body must make adverse compensatory changes for inadequacies in the feet, often resulting in postural

2

trauma existing in many parts of the body. The applicant has suggested that this may be a serious factor in the cause of many major diseases, especially rheumatic fever and cancer.

5 The heel portion of the shoes generally in use tend to have a sharp border which forms an angle of 90° with the ground. In walking or moving the foot, weight is generally first assumed by the borders of the heel portion of the shoe. The sharp angle does not permit the flow of force to be transferred to the sole of the shoe in an efficient manner, such as does the rounded border of the heel of the bare foot during walking. Such a shoe interferes with the efficient functioning of the foot in walking.

10 This invention has as an object to provide a shoe which permits the necessary function of spreading the toes and abducting the great and small toes.

15 20 A further object of this invention is to provide a shoe which prevents deforming pressures against the toes and toe nails.

25 A still further object of the invention is to provide a shoe which eliminates unusual pressures against the tuberosity of the fifth metatarsal bone and the fifth and fourth metatarsal and cuboid articulations, and to adjacent structures due to pressure against the above.

30 Another object of the invention is to provide a shoe which permits a full normal weight bearing surface on the outer side of the foot.

35 Still another object of the invention is to provide a shoe which securely grips the foot at the inner arch, the inner side of the heel and the outer side of the heel, keeping the foot securely positioned in the shoe and yet leaving the forepart of the foot relatively free of pressure and restrictions of movement.

40 45 Still another object of the invention is to provide a shoe in which the rounded border of the heel portion with the vertical permits the weight when taking a step to be easily assumed by the sole of the shoe, the outer border of the heel of the shoe simulating the outer border of the heel of the bare foot.

50 Still further and additional objects and features of the invention will be apparent from the following detailed description read in conjunction with the accompanying drawings.

55 In the drawings:

Figure 1 is a bottom plan view of the left shoe, showing also the location of the foot in the shoe;

Figure 2 is a top plan view of the left shoe;

Figure 3 is a sectional view of the shoe taken along the line III—III of Figure 4;

Figure 4 is a vertical side view of the shoe;

Figure 5 is a sectional view of a modified form of the invention taken along the line V—V of Figure 6;

Figure 6 is a vertical side view of the shoe shown in Figure 5; and

Figure 7 is a fragmentary side view of a still further modification of the invention.

Normal feet are of many sizes and various shapes, but all have basic anatomical and physiological characteristics in common. Thus all normally constructed feet have the same general weight bearing areas in common. These are the heel, the outer side of the foot, the ball of the foot and a large part of the plantar surface of the toes. These areas are indicated in Figure 1 by a continuous line which encloses the space designated and is indicated by the reference numeral 10.

In the present invention as shown particularly in Figure 1, the shoe is so designed that the foot is snugly held in position at points A, B, C, and D, so that the foot is properly positioned centrally of the shoe to allow space at either side of the fore foot for the spreading of the middle toes and abducting of the great and small toes as indicated by dotted lines. Since the heel consists of a single bone, snug fitting at this point does not interfere with the movement of the various joints of the foot while it enables the foot to be securely positioned in the shoe.

To describe the shoe in more detail, it consists of the sole 11 which may extend the entire length of the shoe. In Figure 4, the sole is shown to be flat without the conventional heel, while in Figure 6 the sole is in the form of a wedge. However, a conventional heel may be provided if desired as shown in Figure 7. The posterior and lateral borders of the rear of the sole are curved upwardly as shown at 12 in Figures 3, 4, 5, 6 and 7, in a manner such that a curved border between the rear portion of the sole and the ground is provided which simulates the human heel. The curved border gradually becomes a right angle beginning at the point 13 on the outer side which is behind the calcaneo cuboid articulation, and at the point 14 on the inner side which is posterior to the anterior termination of the sustentaculum tali. The inner surface of the heel or insole 15 may be of any type conventional in the art. This invention is concerned with the outer heel borders of the shoe which come in contact with the ground rather than the inner heel surface that comes in contact with the foot.

The quarter of the shoe 16 can be of any conventional construction except that it must conform to the shape of the pattern of the heel's plantar outline. Counter stiffeners 16' may be used as shown in Figure 5 or the quarter may be flexible according to the need or the use the shoe will be put to. The upper front of the shoe may be provided with perforations 17 as shown in Figures 4 and 6 for lacing the shoe, or if desired straps or other binding devices may be employed to keep the foot firmly positioned in the heel of the shoe. The toe portion of the shoe 18 is relatively high, rising substantially vertically at the toe of the shoe. Too much unused space between the ends of the toes and the end of the shoe is undesirable. The high construction of the toe portion will permit extension of the toes on the foot. A flexible or stiffened toe box may be used according to the needs of the individual.

The present invention resides mainly in the

shape of the sole and plantar surface of the heel of the shoe and hence, it may be applied to any type of shoe that will position the foot in a secure manner. The invention may be applied to shoes used by men, women and children, including the high top shoe, work shoe, oxford, sandal, slipper, overshoes and others. As previously mentioned the heel portion A, B, and C is relatively narrow and shaped to correspond to the human heel so as to snugly fit the heel of the foot. The portion of the foot corresponding to point D is not normally a weight bearing portion of the foot and therefore that portion of the sole can be indented. The sole outline on the inner side of the shoe is provided with an indentation extending toward the foot as shown at D and then flares away from the foot at point 19, which represents the point at which the first metatarsal shaft starts to swell into what will finally become the weight bearing head and sesamoids 20. Thus the foot is snugly held at a point behind the first metatarsal phalangial articulation, and the upper portion of the shoe will fit the inner side of the foot to preclude excessive shifting of the foot in the shoe. No excessive space should be left in the region of the shoe posterior to the first metatarsal phalangial articulation. In the normal or nearly normal foot, the shaft of the first metatarsal 21 is drawn towards the center of the foot when the great toe is abducted thus requiring even less room than when the foot is at rest. This is in contradistinction to the foot that is afflicted with gout or bunions where adduction of the great toe is difficult and excessive bone development and swelling requires a much greater extension of the sole space in this area. This invention is not considered suitable for persons with extensive inflammation and enlargement due to bursitis, gout and grossly enlarged bunions.

At point 22 the border on the inner side of the shoe extends away from the foot to point 22' substantially following a line b'—b'' which is at an angle of approximately 20° to the line a'—a'' which is the axis of the great toe in its normal position. This angle can be varied according to the condition of the individual's foot and his ability to abduct the great toe. The resulting portion of the sole designated as E leaves a space 23 between the edge of the shoe and the great toe when in the normal position. This space 23 is utilized when the great toe is abducted to the position shown in dotted lines in Figure 1 and designated as 24.

The front border of the shoe F conforms to the natural arrangement of the ends of the toes as indicated. This arrangement is distinctly contrary to most present day shoes which are pointed and of excessive length, thus having no relationship to the normal contour of the foot and acting to prevent normal flexion of the toes.

The portion of the shoe G adjacent the small toe extends away from the foot leaving a space 25 between the small toe in its normal position and the outer border of the shoe to permit abduction of the small toe when desired. The border of the sole of the shoe at point G substantially follows the line d'—d'' which is at an angle of approximately 20° with respect to the line c'—c'' which is the axis of the fifth toe and the fifth metatarsal in the normal position. The border of the shoe substantially follows the line d'—d'' from the point 26 which is behind the fifth metatarsal to the point 27 which is anterior of the furthermost extension of the small toe when it is in the abducted position.

The space 25 provided for abduction of the small toe together with the space 23 provided for abduction of the great toe also permits the spreading of the middle toes. Beginning at the point 26, the outer border of the shoe follows the contour of the line 10 to the point 13, thus forming a concave portion 27 adjacent the tuberosity of the fifth metatarsal. The concave portion 27 ends at point 13 behind the cuboid calcaneal articulation. This concave portion 27 permits the tuberosity of the fifth metatarsal, the cuboid bone and its adjacent soft tissues to rest directly on the sole of the shoe. This arrangement is in direct contrast to conventional shoes wherein the sole is convex at this portion of the sole instead of concave so that the foot adjacent this area rests on the upper of the shoe rather than on the sole. The present invention permits this important weight bearing portion of the outer side of the foot to rest on the sole of the shoe.

From the above description it will be readily seen that the foot is snugly positioned within the shoe by the heel, the inner arch, and the outer border, but the outer side of the sole of the shoe is permitted to act as a free weight bearing surface and the front end of the shoe is made high and wide so that no constricting pressures are possible against the toes. The width of the toe portion of the shoe should be approximately twice the width of the widest part of the heel, although this dimension may vary with different shapes and types of feet. The important factor is that sufficient space be allowed on either side of the toes when the foot is secured in the shoe so that abduction of the great and small toes and spreading of the middle toes may be accomplished.

The heel portion of the shoe is curved as shown at 12 on the posterior and lateral borders thus permitting free accession of weight to the sole of the shoe.

The most important features of the present invention may be summarized as follows:

1. A wide toe portion of the shoe extending outwardly at both the inner and outer edges to provide room for the spreading of the middle toes and abducting of the great and little toes.

2. A well fitted heel to snugly position the foot with respect to the shoe.

3. A decided inward contour on the inner side of the shoe to a point behind the first metatarsal phalangial articulation to snugly grip and position the foot with respect to the shoe.

4. An inflare at the region behind the calcaneo cuboid articulation to secure the heel and then a decided flare outward to allow a flat weight bearing surface on the sole for the cuboid and tuberosity of the fifth metatarsal area.

5. A high toe portion of the shoe to permit extension of the toes.

6. A front end of the shoe which conforms to the shape of the composite front ends of the toes and which will permit the shoe to leave the ground with a minimal loss of efficiency.

7. A rounded outer heel border simulating the heel of the bare foot that will permit the sole of the shoe to assume a weight bearing attitude more efficiently.

Although I have herein shown and described the invention in what is conceived to be the most practical and preferred embodiment, it is recog-

nized that departures may be made therefrom within the scope of the invention which is not limited to the details disclosed herein but is to be accorded the full scope of the claims so as to embrace any and all equivalent methods.

Having described the invention what is claimed as new and desired to be secured by Letters Patent is:

1. A shoe construction which prevents deformation of the foot comprising a sole portion, an upper portion, said upper portion including a counter portion and a toe portion, said counter portion being narrow and shaped to securely engage the foot from a point behind the calcaneo cuboid articulation on the outer side thereof to a point on the inner side thereof behind the first metatarsal phalangial articulation, the toe portion of the sole and upper being flared outwardly and forwardly at both the inner and outer edges adjacent the great and small toes to allow spaces between the great toe and the inner edge and between the small toe and the outer edge of the upper portion of the shoe to permit the abducting of said toes, and wherein said shoe additionally includes an outwardly extending curved portion on its outer border adjacent the tuberosity of the fifth metatarsal of the foot to provide for the tuberosity of the fifth metatarsal and its attached soft structures.
2. A shoe construction which prevents deformation of the foot comprising a counter portion, said counter portion being narrow and shaped to securely engage the foot from a point behind the calcaneo cuboid articulation on the outer side thereof to a point on the inner side thereof behind the first metatarsal phalangial articulation, and a wide toe portion, said toe portion being flared outwardly and forwardly at both the inner and outer edges, the inner and outer edges of the shoe from a point adjacent to the weight bearing head and sesamoids to a point adjacent the ends of the great and little toes each flaring outwardly along a line which forms an acute angle with axis of the great and little toes when in their normally extended positions, thereby allowing a space between the small toe and the outer edge of the shoe and between the great toe and the inner edge of the shoe to permit the abducting of said toes, and wherein said shoe additionally includes an outwardly extending curved portion on its outer border adjacent the tuberosity of the fifth metatarsal of the foot to provide for the tuberosity of the fifth metatarsal and its attached soft structures.
